UNITED STATES PATENT OFFICE.

ARTHUR ERNEST SHAW, OF COLUMBIA, SOUTH CAROLINA.

DESIGN FOR A FRAME OR STAND FOR ANESTHETIC-ADMINISTERING APPARATUS.

45,770.

Specification for Design.

Patented May 12, 1914.

Application filed March 19, 1914. Serial No. 825,921. Term of patent 14 years.

To all whom it may concern:

Be it known that I, ARTHUR E. SHAW, a citizen of the United States, residing in Columbia, in the county of Richland and State of South Carolina, have invented a new, original, and ornamental Design for a Frame or Stand for Anesthetic-Administering Apparatus, of which the following is a specification, reference being had to the accompanying drawing, forming part hereof.

Figure 1 is a perspective view of the frame or stand showing my new design, and Fig. 2 is a top plan view thereof.

I claim:

The ornamental design for the frame or stand for an anesthetic-administering apparatus, substantially as shown.

In testimony whereof I have hereunto subscribed my name.

ARTHUR ERNEST SHAW.
